UNITED STATES PATENT OFFICE.

FREDERICK H. MARTIN, OF AKRON, OHIO, ASSIGNOR TO THE B. F. GOODRICH COMPANY, OF NEW YORK, N. Y., A CORPORATION OF NEW YORK.

OVERSHOE.

Application filed April 14, 1923. Serial No. 632,011.

This invention relates to high-topped overshoes of the general type known as galoshes or arctics, and its object is to facilitate the application and removal of the overshoe by decreasing the friction between the lining thereof and the heel of the inner or ordinary shoe.

Galoshes are commonly provided with a heavily napped or fuzzy lining for the sake of warmth, and the contact of such a lining with the heel of the regular shoe makes it somewhat difficult to apply and remove the overshoe if the latter is properly fitted to the wearer's foot, and places an objectionable strain upon the lining and other parts of the upper. This difficulty I overcome in my present invention by the provision of a lining strip or inner facing at the back of the upper of such a nature as to slide easily against the heel of the inner shoe.

Of the accompanying drawings, Fig. 1 is a perspective view of an overshoe provided with my improved anti-friction lining strip.

Fig. 2 is a vertical section of the rear portion of said overshoe.

In the drawings, 10 is an overshoe which may be constructed in the usual or any suitable manner, being here shown with front edges connected by a quick-opening and closing device 11 of the hookless-fastener type.

12 is a bellows tongue, 13 is a cuff at the upper edge, and 14 is a lining of heavily-napped cloth made in two side portions, preferably interrupted by a broad space at

the rear which is filled with an anti-friction strip or facing 15. This strip is made of any suitable cloth of a relatively slippery nature such as mohair or other hair cloth, although I prefer to use for the purpose a 40 cotton sateen cloth which combines a high degree of strength and durability with the necessary smooth surface, besides being comparatively inexpensive.

The strip 15 may be attached to the outer 45 portions of the upper and adjacent parts of the lining in any suitable way, as by coating its back face with adhesive rubber, whereby it becomes firmly united with the other parts when the shoe is vulcanized.

An overshoe having the slippery lining strip 15 in the location specified will go over the wearer's inner shoe with much greater ease than one having the ordinary types of linings heretofore employed.

I claim:

1. An overshoe having a rear lining member of sateen cloth for slipping over the heel of the inner shoe, the said member presenting an uncoated, unimpregnated, sateen surface to the inner shoe.

2. An overshoe having side lining members of heavily-napped cloth and a rear anti-friction lining member of sateen cloth for slipping over the heel of the inner shoe, the 65 said member presenting an uncoated, unimpregnated, sateen surface to the inner shoe.

In witness whereof I have hereunto set my hand this 31st day of March, 1923.

FREDERICK H. MARTIN.
